UNITED STATES PATENT OFFICE

157,666

MAN'S UNDERPANTS OR THE LIKE

Fluta H. Eudy, Fairfield, Calif.

Application July 12, 1948, Serial No. 147,502

Term of patent 14 years

(Cl. D3—17)

To all whom it may concern:

Be it known that I, Fluta H. Eudy, a citizen of the United States and a resident of Fairfield, California, have invented a new, original, and ornamental Design for a Man's Underpants or the like, of which the following is a specification, reference being had to the accompanying drawing, forming part thereof.

Referring to the drawing:

I claim:

The ornamental design for a man's underpants or the like, as shown.

FLUTA H. EUDY.
